FIG. 1 is a perspective view of a golf putter having my new head design.

FIG. 2 is a side view of my golf putter as seen from the back.

FIG. 3 is an end view of my golf putter as seen from the right of FIG. 2.

FIG. 4 is a top plan view of my golf putter.

FIG. 5 is a side view of my golf putter head as seen from the front.

FIG. 6 is an end view of my golf putter head as seen from the left of FIG. 2.

FIGS. 2-6 are shown in fragmentary form for convenience of illustration as the essential feature of my design resides in the putter head.

I claim:

The ornamental design for a golf putter, as shown and described.
